UNITED STATES PATENT OFFICE.

ARTHUR MIDDLETON ROSE, OF YONKERS, NEW YORK, ASSIGNOR TO
MATTHEW J. WHITTALL, OF WORCESTER, MASSACHUSETTS.

DESIGN FOR CARPET.

SPECIFICATION forming part of Design No. 25,257, dated March 17, 1896.

Application filed February 10, 1896. Serial No. 578,806. Term of patent 3½ years.

To all whom it may concern:

Be it known that I, ARTHUR MIDDLETON ROSE, a citizen of the United States, residing at Yonkers, in the county of Westchester and State of New York, have invented and produced a new and original Design to be wrought into Wilton and other Carpeting, in such coloring as may be designed, of which the following is a specification.

10 This invention comprises two parts—namely, the design A for a carpet-body and the design B for a border; and I do hereby declare that the drawing accompanying this specification gives and conveys to any one skilled in the art of carpet weaving and manufacture a clear understanding of same and is sufficient to enable such person to use my invention.

15 The body A shows a circular figure and spray appearing at intervals on a figured

groundwork. The border B shows similar groundwork near the inner edge, also groups of the circular figures and sprays with scroll-work toward the outer edge.

What I claim as my invention, and desire to secure by Letters Patent, is—

1. In a design for a carpet, the body A, substantially as shown.

2. In a design for a carpet, the border B, substantially as shown.

3. The design for carpets, consisting of the body A and the border B, substantially as shown.

In testimony whereof I have hereunto set my hand in the presence of two subscribing witnesses.

ARTHUR MIDDLETON ROSE.
